UNITED STATES PATENT OFFICE.

WILLIAM H. MAUPIN AND DICE R. LOBDELL, OF LEMMON, SOUTH DAKOTA.

INTERNAL-COMBUSTION ENGINE.

1,204,296.

Specification of Letters Patent. Patented Nov. 7, 1916.

Application filed February 11, 1915. Serial No. 7,514.

To all whom it may concern:

Be it known that we, WILLIAM H. MAUPIN and DICE R. LOBDELL, of Lemmon, in the county of Perkins and State of South Dakota, have invented certain new and useful Improvements in Internal-Combustion Engines; and we do hereby declare the following to be a full, clear, and exact description of the invention, such as will enable others skilled in the art to which it appertains to make and use the same.

The primary object of this invention is to provide an improved internal combustion engine which will be practically noiseless in operation, comparatively simple in construction, and which may be manufactured at relatively less cost than has heretofore been possible in this class of engines.

A further object of our invention is to prevent or lessen the formation of carbon on or around the sparkler.

In the accompanying drawings, Figure 1 is a side elevation, partly in section, and with parts broken away. Fig. 2 is an enlarged transverse sectional view through one of the cylinders, showing the valve mechanism for controlling the intake and exhaust. Fig. 2^a is a detail. Fig. 3 is a sectional view showing the oil-feeding means. Fig. 4 is a sectional view at right angles to Fig. 3. Fig. 5 is a plan view, in section, of the parts shown in Figs. 3 and 4, the outlines of two of the cylinders being indicated. Fig. 6 shows in section a slightly modified form of mechanism for operating the controlling valve. Fig. 7 is an enlarged sectional view of one of the valves and operating mechanism shown in Fig. 6. Figs. 8 and 9 are details.

Referring to the drawings, 1 designates the crank casing; 2 the piston cylinders, four in number; 3 the crank-shaft suitably journaled in casing 1; 4 the fly-wheel; and 5 the clutch, a portion only of which is indicated, in Fig. 1. The fly-wheel and clutch are shown inclosed in an extension 6 of casing 1, and in the fly-wheel we form a port 7 coinciding with a centrally arranged port 8 extending longitudinally through the crank shaft and connected through the several piston rods 9 with the pistons 10 fitted in cylinders 2, said pistons having lateral outlets for the oil. By this arrangement the oil is distributed to the main bearings, wrist-pins and cylinder walls.

Each of the piston cylinders at its upper

end opens through a centrally-located port 12 (Fig. 2) into a cylindrical chamber extending at right angles thereto, said chamber at its end 13 forming the intake-port, and at its end 14 the exhaust-port, said intake-port being connected to the air and gas supply manifold. In vertical alinement with the port 12 is the spark plug which is conventionally indicated at 15 located in a bore of preferably the same diameter as and in line with port 12. The intake and exhaust of each cylinder are controlled by a sliding piston-valve 16 which is formed with a port 17 extending transversely therethrough and designed to coincide with port 12 and the spark plug when the charge is to be ignited, as shown in Fig. 2. After ignition and the descent of the piston of the respective cylinder, the piston valve 16 is moved to the left, Fig. 2, sufficiently far to uncover port 12 so that on the return stroke of the piston the burnt gases will be exhausted through port 12, the cylindrical chamber and port 14 either direct to the atmosphere or indirectly through a muffler, according to known means. The piston valve is then quickly moved in the opposite direction to place port 12 in communication with the intake end 13 of the chamber, so that on the suction stroke of the piston the charge will be drawn into the cylinder. By the time the piston reaches the end of its compression stroke valve 16 will be in its central position, as shown in Fig. 2, so that the charge may be ignited by the spark through the coincident ports 12 and 17. For the purpose of preventing fouling the spark plug and its chamber by the burnt gases, we form the piston valve 16, at its top, with an end flange or extension 18 which will entirely cover the lower end of the spark plug chamber when the piston valve is positioned to allow the exhaust of the burnt gases.

The means for operating the several piston valves may be widely varied, two forms of such means being shown. According to the preferred means the rods 19 of the several piston valves are formed with yokes 20, each yoke carrying two laterally disposed, oppositely-extended, rollers 21 with which are designed to engage cams 22 fast on a common shaft 23 extending longitudinally of a casing 24 secured to the main casing of the engine and into which open the supply ducts. These cams are so formed as to impart to the several piston valves the neces-

sary reciprocation transversely of the ports 12 of the several piston cylinders. The cam carrying shaft 23 is suitably journaled in casing 24 and is rotated by a chain-belt 25 driven by crank shaft 3, as indicated in Fig. 1.

A different form of mechanism for operating the piston valves is shown in Figs. 6 and 7. According to the means there shown

10 the valve rods 19^a are connected at their outer ends to shifting arms 30 which are pivoted at their upper ends in a chamber 31 of the engine casing, said arms 30 being extended through slots in the bottom of 15 such chamber. Fast on the pivot of each of the several arms 30 are two diagonally arranged arms 32 which carry rollers 33 with which are designed to engage cams 34 on a cam shaft 23^a which is designed to be 20 operated in timed relation to the crank shaft. In order to allow arms 30 to be swung transversely of the axis of the cam-actuated shaft such arms are formed with lateral loops 35 as shown in Fig. 7. While 25 this construction has certain advantages, we prefer that first hereinbefore outlined. Of course, any suitable means may be employed for imparting the necessary reciprocation to the piston valves.

30 40 designates a series of sight-feed oil cups, each of which communicates through a bore 41 with one of the piston valve chambers, and in this connection it will be noted, by reference to Figs. 2 and 7, that each of 35 the piston valves has a horizontal flange 42 which travels back and forth beneath bore 41 and serves to distribute the lubricant in the valve chamber. The several oil-cups are connected in series by a common pipe 43 through 40 which oil is supplied to the several cups and which pipe is also designed to supply lubrication to the bearings of the cam-shaft 23. To the pipe 43 is connected a supply pipe 44 (Figs. 3, 4 and 5) which leads from a 45 reservoir 45, or, more properly speaking, from a force feeder 46 located within the reservoir. The force feeder comprises a cylinder wherein a piston 47 is designed to be reciprocated, being moved in one direction by a cam 48, on cam shaft 23, and in the opposite direction by the recoil of a spring 49. When the piston moves outwardly oil is drawn into its cylinder by the unseating of an inwardly-moving valve 50, and when moved in the opposite direction an outlet valve 51 is unseated, such latter valve controlling communication with pipe 44. The reseating of valve 51 on the

suction stroke of the piston prevents oil from being drawn back through the supply pipe. Any over-pressure within the piston-cylinder will be automatically relieved by the unseating of a relief valve 52, which is normally held seated by a spring 53. By the described means the lubricating oil may be continuously supplied from the reservoir to the several oil-cups and bearings.

60 By means of the cylinder valves, we are enabled to provide relatively large intake and exhaust ports, and by reason of the 70 positive reciprocation of such valve, without the use of springs, not only is noise eliminated but the wear occasioned by the use of numerous cams and shaft-bearings is avoided, or materially reduced. Furthermore, by the use of this valve ignition will occur at the axial center of the cylinder, thereby insuring the distribution of the full 75 force of the explosion equally against the face of the piston; and since the ignition 80 occurs centrally of and within the valve the force of the explosion does not tend to unseat the valve. By protecting the spark-plug during the exhaust stroke carbonization 85 thereof is avoided or greatly reduced.

85 It will be noted that the force feed oiler is out of the way, being located wholly within the oil reservoir which latter may be 90 readily supplied with oil and access gained thereto for cleaning purposes. The means employed for forcing the oil supply is extremely simple and positive in operation.

95 We have not described any means for cooling the cylinders, since any suitable means may be employed.

We claim as our invention:

100 In an internal combustion engine, the combination with a cylinder having a central port at its top, a spark in vertical alignment with said port, a chamber above said cylinder and intermediate the latter and said spark, a reciprocating piston movable in said chamber for controlling said port, said piston having a port designed to align with said spark and said cylinder-port, and a projection carried by 105 said piston for covering said spark when said cylinder is exhausting.

110 In testimony whereof we have signed this specification in the presence of two subscribing witnesses.

WILLIAM H. MAUPIN.
DICE R. LOBDELL.
